DISPENSING CONTAINER FOR PILLS

Carroll H. Walter, Westmount, Quebec, Canada, assignor, by mesne assignments, to Syntex Corporation, Panama,
Panama, a corporation of Panama

Filed July 1, 1968, Ser. No. 12,580

Claims priority, application Canada May 28, 1968

Term of patent 14 years

Int. Cl. D9—04

U.S. Cl. D9—184

FIG. 3

FIG. 1

FIG. 4

FIG. 5

FIG. 1 is a top plan view of a dispensing container for pills showing my new design;

FIG. 2 is a front elevational view;

FIG. 3 is an inverted rear elevational view;

FIG. 4 is a side view looking from the right of FIG. 1, and

FIG. 5 is a bottom plan view thereof.

I claim:

The ornamental design for a dispensing container for pills, as shown.
